REFRIGERATOR WAGON

Clarence C. Hewitt and Clarence A. Hewitt,
Gettysburg, Pa.

Application October 31, 1950, Serial No. 12,796

Term of patent 7 years

(Cl. D14—3)

To all whom it may concern:

Be it known that we, Clarence C. Hewitt and Clarence A. Hewitt, residing at Gettysburg, in the county of Adams, in the State of Pennsylvania, have invented a new, original, and ornamental Design for a Refrigerator Wagon, of which the following is a specification, reference being had to the accompanying drawing, forming a part hereof.

Fig. 1 is a perspective view of a refrigerator wagon, showing our design; Fig. 2 is a side elevational view; Fig. 3 is a plan view; and Fig. 4 is a front elevational view.

We claim:

The ornamental design for a refrigerator wagon, as shown.

CLARENCE C. HEWITT.
